UNITED STATES PATENT OFFICE.

CHARLES STOLLBERG, OF NEW YORK, N. Y., ASSIGNOR TO AMERICAN CAN COMPANY, OF NEW YORK, N. Y., A CORPORATION OF NEW JERSEY.

CONTAINER.

Application filed November 28, 1921. Serial No. 518,203.

To all whom it may concern:

Be it known that I, CHARLES STOLLBERG, a citizen of the United States, residing in New York, in the county of Kings and 5 State of New York, have invented a new and useful Improvement in Containers, of which the following is a specification.

This invention relates to containers and a method of forming the same, having to do 10 more particularly with that type of container adapted for the packaging of lead, paint and other heavy materials.

A principal object of the invention is the provision of a lead keg provided with an 15 end closure secured thereto in especially strong and effective manner, and by a method particularly suited to the forming of a container of desired construction for the purpose stated.

20 A further object of the invention is the provision of a lead keg or like container having a solid wired edge upon which the container may be rolled, said edge preferably corresponding in general form to that provided at the opposite end of the keg.

25 Still another object of the invention is the provision of a container of the character specified, in which a firm union is obtained between the end and container body, and the 30 outwardly extending portion of the cover is brought to desired form by easily performed operative steps, resulting in a highly efficient end formation.

35 A still further object of the invention is the provision of a container having the foregoing characteristics in which the body portion to which the cover is attached may be substantially straight and requires no special or difficult formation.

40 A general object of the invention is the provision of a highly efficient container for packaging lead and like material which is capable of practical commercial production and use, with particular economy and generally desirable results.

45 Numerous other objects and advantages of the invention will be apparent as it is better understood from the following description, which, taken in connection with the accompanying drawings, discloses a preferred embodiment thereof.

Referring to the drawings,

50 Figure 1 is a side elevation of a container in which my invention is embodied, a por-

tion thereof being broken away to show certain parts in section;

Fig. 2 is an enlarged detail section showing the zone of welding and the outwardly extending end flange prior to its being formed about the wire; and

Fig. 3 is a similar section showing the wired edge in final form.

Upon the drawings, which illustrate the invention, I have shown a container body 11 provided with a cover 12, which may be of any suitable or preferred form through 55 preferably having a rounded projecting portion, as indicated at 13, and a bottom end 14 secured by a method which forms an important part of my invention. The cover 60 12 is first applied and secured to the body, in desired manner, and may be provided with a wired edge for a purpose which will 65 hereinafter appear.

The bottom 14 has a depressed or plug 70 portion 15 adapted to be inserted into the body of the container, and, in accordance with my invention, is welded to the interior of said body about a zone 16, indicated by dotted lines in Fig. 2. This end is applied 75 with a substantially straight flange 17 extending outwardly from the container body. The flange 17 is subsequently folded, as indicated in Fig. 3, about a wire 18, and the wired edge thus formed lies in contact with 80 the straight edge 19 of the container body. With the inner wall 21 welded to the interior 85 of the container, a firm union is provided between the end and said body and the body edge need not be enclosed in the curl of the 90 flange 17 about the wire 18.

Containers of this character are frequently very heavy when filled and may be best handled by rolling upon the floor or ground. With the wired edge which I have provided 95 at the bottom, and the usual similar edge provided at the top, the keg may be readily rolled and handled as occasion may demand. Furthermore, with the end firmly secured by welding, there is no likelihood of its being accidentally removed, and a tight seal 100 is provided. The cover is preferably attached with a suitable gasket interposed between the body and cover flanges, and the container may therefore be hermetically 105 closed.

It is thought that the invention and many of its attendant advantages will be under-

stood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

- 10 1. A container comprising a tubular body having a flangeless end portion, an end member welded to the body continuously along a zone extending entirely around the body, and having an outwardly extending flange, and a wire enclosed within said flange in a

roll on the outside of the container, said roll gripping the wire against the side of the body and thereby reinforcing the welded joint.

2. A container comprising a tubular body 20 having an end portion, an end member welded to the body continuously along a zone extending entirely around the body and having an outwardly extending flange, and a wire enclosed within said flange in a roll 25 on the outside of the container, said roll gripping directly against the wire and holding the wire against the side of the body and thereby reinforcing the welded joint.

CHARLES STOLLBERG.
